UNITED STATES PATENT OFFICE.

ALPHA HORATIO METCALF, OF ATTLEBORO, MASSACHUSETTS, ASSIGNOR TO THE BAER & WILDE COMPANY, OF ATTLEBORO, MASSACHUSETTS, A CORPORATION OF MASSACHUSETTS.

SHIRT STUD.

Application filed April 23, 1926. Serial No. 104,018.

This invention relates to a new and improved method of making shirt studs and similar articles and to a new and improved shirt stud or the like.

5 One of the objects of this invention is to provide a shirt stud comprising a one-piece body and a one-piece movable shank provided with an ornamental head which can be conveniently and cheaply manufactured.

10 Another object is to provide a device which shall be substantially dust-proof.

Another object is to provide a simple, durable, and efficient spring detent which shall 15 releasably hold the shank in two positions.

Other objects of this invention will be set forth in the following description and drawings, which illustrate a preferred embodiment thereof, it being understood that 20 the above general statement of the objects of this invention is intended merely to generally explain the same and not to limit it in any manner.

Fig. 1 is a front elevation showing the 25 improved stud applied to a shirt.

Fig. 2 is a front elevation of the stud.

Fig. 3 is a side elevation of the stud, shown applied to a shirt.

Fig. 4 is an elevation of the tubing used 30 for making the device.

Fig. 5 is a section on the line 5-5 of Fig. 4.

Fig. 6 is a side elevation illustrating the first step in the manufacture of the device.

35 Fig. 7 is a front elevation of the article shown in Fig. 6.

Fig. 8 is a side elevation showing another step in the manufacture of the device.

Fig. 9 is a section on the line 9-9 of 40 Fig. 8.

Fig. 10 is a sectional view, partially in elevation, showing the completed device, the shank being shown in its intermediate position.

45 Fig. 11 is a view similar to Fig. 10, the shank being shown in its inner position.

Fig. 12 is a view similar to Fig. 10, the shank being shown in its outer position.

50 Fig. 13 is a view similar to Fig. 10, the spring detent being omitted.

A piece of tubing 1 made of gold or any other metal, is provided with an aluminum core 2. The straight section 1' is bent by means of suitable dies or the like to provide

it with a leg 4, which is formed as shown 55 in Fig. 6, by the bending operation.

A hole 3 is now formed in the tube 1 and a depression in the aluminum core is simultaneously formed as shown in Fig. 6. The aluminum core is now removed by treatment with any suitable acid, which will not affect the gold tube. The removal of the core is facilitated by the formation of the opening 3.

65 A mandrel M, made of steel or other hard metal, is forced through the opening 3, so that the point of the mandrel emerges from the top of the leg 4, as shown in Fig. 8. The cross-section of mandrel M is non-circular, and this mandrel is preferably provided 70 with two opposite, parallel and equal planar faces, and with two convex faces, as shown in Fig. 9. The mandrel M shapes the interior of the leg 4 so that its cross-section is no longer circular, and it is given a shape 75 corresponding to the shape of the mandrel M.

The top of the leg 4 is now expanded and bent to form a head 9, this operation per se 80 being well-known.

85 A shank 6, provided with two recesses 7 and 8 and having an ornamental head 10, is now inserted into the leg 4. The shank 6 has a shape corresponding to the shape of the mandrel M, so that it slides in the leg 4 without turning, and it fits snugly in 90 leg 4, to exclude dust as much as possible.

The shank 6 is placed in the leg 4 in the position shown in Fig. 3 (but without closing the end of tube 1); the ball 12 and the 95 compression spring 11 are placed in position, and the end of the tube 1 is closed.

The compression spring 11 now forces the ball 12 against the shank 6, so that the ball 12 acts as a detent, to releasably hold the shank in either of the two positions shown in Figs. 11 and 12. In these positions, the ball 12 engages either the recess 7 or the recess 8.

When the parts of the device are in the 100 position shown in Fig. 12, the body 1 can be forced through two adjacent stud-openings in a shirt S, so that said body portion 1 assumes the position shown in Figs. 1 and 3. By then pushing on the ornamental shank head 10, the shank is forced into the 105 position shown in Fig. 3, to lock the two parts of the shirt to each other.

To remove the stud, the parts are moved into the position shown in Fig. 12, when the stud can be readily pulled out.

It is obvious that the device can be readily manipulated, and that it is far more convenient to use than studs heretofore known.

The shank cannot be withdrawn from the leg 4, because the inner end of said shank is provided with a hook-like extension 14.

10 An important feature of this invention is that spring detent means are provided which are independent of the tubing used. Hence, there is no need to make this tubing resilient *per se*.

15 The flange 9 should be so wide that it does not pass through the shirt opening.

20 A preferred embodiment of this invention has been described, but it is clear that numerous changes and omissions could be made 25 without departing from its spirit. In particular, the claims for the article are not to be restricted to any particular method of producing the same. Whenever a shirt-stud is referred to in the description or claims, 30 this is to be understood as referring to and including all similar articles.

I claim:—

35 1. A shirt stud comprising a hollow body portion having a hollow leg provided with an enlarged top portion, said body portion and said leg comprising two parts of an integral bent tube, the cross-section of said leg being non-circular, said leg having an opening adjacent the inner end thereof, and a 40 slideable shank having a non-circular cross section corresponding to the cross-section of said leg and slidably fitting within said leg and being held from turning in said leg, said shank having a head.

45 2. A shirt stud comprising a body portion having a hollow leg provided with an opening adjacent the inner end thereof, a slideable shank located within said leg, and spring detent means independent of the material of said leg and adapted to releasably engage said shank, said shank having a head.

3. A shirt stud comprising a hollow body portion having a hollow leg, said leg having an opening adjacent the inner end thereof,

50 a slideable shank having a head and located within said leg; and spring detent means located in said body portion and adapted to engage said shank.

4. A shirt stud having a body portion and a hollow leg provided with an opening adjacent the inner end thereof, a slideable shank having a head and located within said leg, said shank having a plurality of recesses in the face thereof adjacent to said body portion, a compression spring located in said body portion, and a detent member actuated by said spring and adapted to enter said recesses to releasably engage said shank.

5. A shirt stud having a hollow body portion and a hollow leg provided with an opening adjacent the inner end thereof, said body portion and said leg comprising two parts of an integral bent tube, said leg being provided with an inner wall having two opposite and substantially planar faces, and a shank 70 having a head, said shank being slidably located in said leg and having two substantially planar faces in slideable relationship to the substantially planar faces of the inner wall of the leg.

6. A shirt stud having a body portion and a hollow leg provided with an opening adjacent the inner end thereof, a slideable shank having a head and located within said leg, spring detent means independent of the material of said leg and adapted to releasably engage said shank, said shank having a hook-like extension at the inner end thereof adapted to engage the outer wall of said leg.

7. A shirt stud having a hollow body portion and a hollow leg provided with an opening at the inner end thereof, said shank having two concave recesses on the face thereof adjacent said body portion, a ball located in said body portion and adapted to engage said recesses, and a compression spring located in said body portion and adapted to urge said ball to engage said recesses.

8. A device according to claim 7 in which the inner wall of said leg and said shank have corresponding non-circular contours.

In testimony whereof I affix my signature.

ALPHA HORATIO METCALF.
